DESIGN FOR AN OUTSIDE DOOR HANDLE OR SIMILAR ARTICLE FOR AN AUTOMOTIVE VEHICLE

Clare M. MacKichan, Detroit, Mich., assignor to General Motors Corporation, Detroit, Mich., a corporation of Delaware

Application January 3, 1947, Serial No. 135,929

Term of patent 7 years

(Cl. D10—8)

To all whom it may concern:

Be it known that I, Clare M. MacKichan, a citizen of the United States, residing at 18406 Westhaven Avenue, Detroit, in the county of Wayne and State of Michigan, have invented a new, original, and ornamental Design for an Outside Door Handle or Similar Article for an Automotive Vehicle, of which the following is a specification, reference being made to the accompanying drawing, forming part thereof.

Fig. 1 is a perspective view of an outside door handle or similar article for an automotive vehicle, showing my new design;

Fig. 2 is a top plan view of the same;

Fig. 3 is a front elevation of the same;

Fig. 4 is a section along the line 4—4 of Fig. 3.

Fig. 5 is a section along the line 5—5 of Fig. 2.
Fig. 6 is a section along the line 6—6 of Fig. 3.

I claim:

The ornamental design for an outside door handle or similar article for an automotive vehicle, substantially as shown.

CLARE M. MACKICHAN.
